AUTOMOBILE STORAGE TROUGH

Roger W. Kirkby, 1401 Greenview, East Lansing, Mich.

Filed June 24, 1965, Ser. No. 85,885

Term of patent 14 years

(Cl. D14—6)

FIG. 1 is a side elevational view of an automobile storage trough showing my new design;

FIG. 2 is a top plan view thereof;

FIG. 3 is a bottom plan view thereof;

FIG. 4 is a front view thereof;

FIG. 5 is a rear view thereof; and

FIG. 6 is a perspective view thereof.

The portions shown in broken lines are included for illustrative purposes only.

I claim:

The ornamental design for an automobile storage trough, as shown and described.
